F. S. BENNETT

VALVE MECHANISM

Filed Feb. 14, 1920

Inventor:
Frank S. Bennett,
by Almudh, Davis
His Attorney.

UNITED STATES PATENT OFFICE.

FRANK S. BENNETT, OF SCHENECTADY, NEW YORK, ASSIGNOR TO GENERAL ELECTRIC COMPANY, A CORPORATION OF NEW YORK.

VALVE MECHANISM.

Application filed February 14, 1920. Serial No. 358,733.

To all whom it may concern:

Be it known that I, FRANK S. BENNETT, a citizen of the United States, residing at Schenectady, in the county of Schenectady, 5 State of New York, have invented certain new and useful Improvements in Valve Mechanisms, of which the following is a specification.

The present invention relates to valve 10 mechanisms such as are used to control the flow of elastic fluid to turbines and the like and has for its object to provide an improved arrangement in a device of this character.

15 For a consideration of what I believe to be novel and my invention, attention is directed to the accompanying description and claims appended thereto.

In the drawing, the figure is a sectional 20 view of a valve mechanism embodying my invention, the same being shown by way of example as embodied in a structure particularly intended for use in controlling the flow of elastic fluid to the ahead and reverse 25 turbines or turbine sections of a marine turbine. It will be understood, however, that the invention is not limited to such a structure.

Referring to the drawing, 5 indicates a 30 valve casing having walls forming an admission chamber 6 and two separate discharge chambers 7 and 8. Connected to admission chamber 6 is a supply conduit 9, and leading from discharge chambers 7 and 35 8 are discharge conduits 10 and 11 respectively which may lead to separate turbines or turbine sections for supplying operating fluid thereto. The flow of elastic fluid from admission chamber 6 to discharge chambers

40 7 and 8 is controlled by valves 12 and 12^a which are shown as being of like structure. The stems 13 and 13^a of valves 12 and 12^a are tubular in form and at their outer ends connect to balancing pistons 14 and 14^a 45 which slide in cylinders 15 and 15^a respectively. The inner ends of valves 12 and 12^a are guided by sleeves 16 and 16^a, and are each provided with pilot valves 17 and 17^a which engage seats on the inner ends

50 of valve stems 13 and 13^a and control the admission of operating fluid to cylinder 15 and 15^a. The stems 18 and 18^a of pilot valves 17 and 17^a pass through suitable stuffing boxes 19 and 19^a in the valve cas-

ing and at their outer ends are connected 55 to operating levers 20 and 20^a which move over quadrants 21 and 21^a and are provided with suitable latches as indicated at 22 and 22^a for fastening the valves in any desired 60 position.

The foregoing is a known type of valve structure and its operation is well understood. When the valves 12 and 12^a are closed, the fluid pressure in admission chamber 9 acts on them to hold them tightly on their seats, the valves being thus biased to closed position. Pilot valves 17 and 17^a are also on their seats which cuts off communication between admission chamber 6 and cylinder 15 and 15^a. The pressure in cylinder 15 and 15^a behind pistons 14 and 14^a will be that found in discharge chambers 7 and 8, as the pressures on opposite sides of such pistons become equalized due to gradual leakage past the pistons. In opening a valve, for example, valve 12, when the operating lever 20 is moved the pilot valve 17 will be first opened to admit operating fluid from chamber 9 around the pilot valve stem 18 to the balancing cylinder 15, thereby equalizing or substantially equalizing the pressure on valve 12, which can then be easily opened as it will be substantially balanced. The degree of 70 balance will depend, of course, upon the relative areas of valve 12 and piston 14, and by choosing proper areas the valve when opened may be biased slightly toward either 75 open position or closed position.

When a valve structure of the type described above is used to control the admission of elastic fluid to a prime mover, such as a turbine, it is the practice to provide in advance of it, as regards the flow of elastic fluid, a suitable emergency shut-off valve 90 which is biased toward closed position and is adapted to be tripped either manually or automatically as by an emergency governor and caused to close. In the drawing, such an emergency valve is indicated at 24. It is shown as being a clapper type valve adapted to engage a seat 25 and as having a spindle 26 to which is connected a lever arm 27. Connected to the end of arm 27 is an operating rod 28 which extends to an emergency tripping mechanism (not shown). For example, such tripping mechanism may be of the type shown in the ap- 100 105

lication of Edgar D. Dickinson, Serial No. 289,032, filed April 10, 1919, or of other suitable type.

With the foregoing arrangement, assume that the invention may be carried out by other means. 55
5 that the emergency valve 24 is open and a valve, as the valve 12, is partially open and supplying elastic fluid to a turbine for example. Under these conditions the pressures in admission chamber 6, discharge 10 chamber 7 and in cylinder 15 behind piston 14 is that of the high pressure elastic fluid. If now, due to some cause, the emergency valve 24 is tripped and closed, then the pressures in chambers 6 and 7 will immediately 15 drop becoming equal to that which exists at the exhaust end of the turbine, and high pressure elastic fluid will be trapped in cylinder 15 and exert a heavy pressure tending to open the valve. Under these circumstances, if the operative, before the pressure has leaked out of cylinder 15, starts to 20 close valve 12 for the purpose of again starting up the machine, as soon as he releases latch 22 the pressure back of piston 14 will instantly throw the valve to wide 25 open position with considerable force and with danger of injury to the operative. More particularly, the object of my invention is to provide an arrangement which will prevent an accident of this character happening, 30 and to this end I provide an equalizing pipe or conduit 30 which connects the admission chamber 6 with the cylinders 15 and 15^a, and in such pipe or conduit I provide a check 35 valve 31 which prevents the flow of fluid from chamber 6 to the cylinder but permits it to flow from the cylinder to chamber 6. With this arrangement it will be seen that the pressure in cylinders 15 and 15^a can 40 never be greater than that in chamber 6 and that in case the emergency valve 24 closes under the conditions set forth above, the pressure in cylinders 15 or 15^a will be instantly relieved through conduit 30 so the 45 operative may immediately close such valve without danger of accident.

In accordance with the provisions of the patent statutes, I have described the principle of operation of my invention, together 50 with the apparatus which I now consider to represent the best embodiment thereof, but I desire to have it understood that the apparatus shown is only illustrative and

that the invention may be carried out by other means.

55

What I claim as new and desire to secure by Letters Patent of the United States, is:—

1. In a valve structure, the combination of a casing having a seat, a main valve adapted to engage said seat, a cylinder, a balancing piston for the main valve, which piston is located in said cylinder, conduit means connecting the admission side of the valve casing to said cylinder, a pilot valve in said conduit means, an additional conduit 60 means independent of the pilot valve connecting the valve casing on the admission side of the main valve to said cylinder. 65

2. In a valve structure, the combination of a casing having a seat, a main valve adapted to engage said seat, a cylinder, a balancing piston for the main valve, which piston is located in said cylinder, a pilot valve for the main valve, conduit means connecting the valve casing on the admission side of the main valve to said cylinder, and a non-return valve in said conduit which 70 opens toward the valve casing. 75

3. In a valve structure, a valve casing having an admission chamber and a plurality of discharge chambers, a main valve between said admission chamber and each discharge chamber, a balancing piston and a pilot valve for each main valve, conduit means controlled by said pilot valves, a cylinder for each balancing piston, conduit means independent of said pilot valves connecting said admission chamber to each of said cylinders, and check valve means in 80 said conduit means. 85

4. A valve structure comprising a main valve, a cylinder, a balancing piston therein, and a pilot valve controlling the admission of fluid to the cylinder characterized by the fact that in connection with such valve structure a conduit is provided which connects the cylinder to the admission side of the main valve and contains a non-return valve which opens away from said cylinder, whereby the pressure in the cylinder can 95 never exceed that on the admission side of the main valve. 100

In witness whereof, I have hereunto set my hand this 12th day of February 1920.

FRANK S. BENNETT.
